EXTENSIBLE HANDLE

Charles H. Nehls, Detroit, Mich.

Application December 11, 1936, Serial No. 115,297

3 Claims. (Cl. 292—347)

This invention relates to retractable operating handles for doors and the like, and particularly concerns handles of the variety which when not in use lie close to or flush with the door or other surface upon which they are mounted. An important object of the present invention is to provide such a door handle, particularly adapted to serve as operating means for the latch of an automobile door, so constructed that no special configuration of the door or special latch construction is required, such elements being utilizable in constructions and arrangements now in use and regarded as more or less conventional. A further object is an improved extensible handle requiring no special manipulation or effort to extend the handle, such extension being caused naturally, if not unconsciously, by the user in grasping the handle with his fingers in the normal manner of operating vehicle door locks of conventional construction.

Other objects and advantages will be apparent from the following description, wherein reference is made to the accompanying drawing illustrating a preferred embodiment of my invention, and wherein similar reference numerals designate similar parts throughout the several views.

In the drawing:

Figure 1 is a horizontal cross-sectional view of an automobile door of hollow metal construction, equipped with a door latch operable by handle means incorporating the principles of this invention, such handle means being shown in section.

Figure 2 is a front elevational view of the handle, mounted upon the door, the latter being fragmentarily shown.

Figure 3 is a vertical section taken substantially on the line 3—3 of Figure 2 and looking in the direction of the arrows.

Figure 4 is a horizontal section taken substantially on the line 4—4 of Figure 3, and looking in the direction of the arrows.

Figure 5 is a fragmentary elevational view taken as indicated by the line 5—5 of Figure 1, and looking in the direction of the arrows, parts being broken away to afford a better view of the interior construction.

Figure 6 is a detailed perspective view showing the spring backing means and method of mounting the same upon the shank or handle shaft.

Referring now to the drawing, reference character 10 designates the front or outer panel of a vehicle door, shown as of hollow sheet metal construction and adapted to be swingable in the usual manner into and out of a doorway provided in the body 12. A latch 15 mounted inside the door is provided with a latch bolt 16 projectable from the edge of the door to engage a striker plate 17 on the door jamb. Only the outside operating means for the latch is shown. The latch mecha-

nism, also, may be of any desired or usual construction, and accordingly its details of construction are not shown. The outside operating means comprises a handle 20, of the lever type, provided at its pivoted end with a partly spherical surface 5 forming a ball portion 22, and mounted in a corresponding partly spherical socket 24 in the handle-supporting plate 26. Such plate also serves as an escutcheon, being shown secured to the face 10 of the door by screws 27.

Guiding means are provided in the form of pin and slot portions 32—33, the former carried by the ball section of the handle and the latter punched or otherwise formed in the socket portion 24, such pin and slot connection serving 15 to guide the handle and prevent turning thereof until it has been pulled away from the door, thus protecting the finish of the door against being streaked or marked by dragging of the end portion 21 of the handle thereover.

The handle normally extends horizontally, and when pulled away from the face of the door, substantially to the position indicated in dot-dash lines at 20A in Figure 1, is rockable to turn the latch-operating shaft or shank 25. The shank is provided at its outer end with an enlarged head portion 39 which is vertically apertured and provided with flat and parallel top and bottom surfaces, over which the handle, slotted as at 21' to receive the head, is fitted, and to 30 which it is pivotally attached by means of a pivot pin 30 extending through the aperture 40 in the ball portion of the handle, and through aperture 28 in the head of the shank.

A torsion spring 35 also housed in the aperture 35 28 acts to return the handle to its normal rest position against the face of the door, such position being that shown in full lines in Figure 1. The spring is wrapped loosely about the pin 30. A radial slot 36 in one face of the head intersects the opening 28 to hold one end of the spring, which is out-turned thereinto, while at its other end the spring acts upon the pin 39, which turns as a unit with the handle, the spring extending through a slot 38 in the pin. The construction 40 of these parts may best be understood by a description of the method of installation of the pin, which is provided at its end with a reduced and knurled area 37 through which the spring slot 38 extends. Such reduced and knurled portion 37 45 extends. Such reduced and knurled portion 37 is harder and somewhat larger than the counterbored bottom portion 41 of the bore 40 in the handle in which the pin is held, the knurled and counterbored portions 37—41 being so proportioned that when the pin is driven into place, 55 it is tightly held against turning with respect to the handle by the knurling and tight fit.

In order to apply the desired torsion to the spring and handle, the spring is first fitted into the opening 28 in the shank head, with its out- 60

turned end 35A held in the slot 36, and its opposite end 35B extending diametrically across the other end of the opening 28. The handle is then fitted over the head of the shank, and its bore 40 aligned with the transverse opening 28. The pin is inserted from the end opposite to the diametrically extending end portion 35B of the spring, and the slot 38 of the pin fitted over such spring portion. Thereafter, before the knurled portion 10 37 of the pin is driven into the counterbore 41 in the handle, the pin is turned to apply torsion to the spring, as by means of a screw driver or other suitable implement engaged in the slot 44 provided in the head of the pin for the purpose. 15 With the pin so held in its turned position by means of the screw-driver, the end of the screw-driver is struck, as with a hammer, to drive the pin home, whereafter its tight fit in the bore portion 41 holds it and the spring end 35B against 20 turning with relation to the handle.

It will be understood that the above-described operations are performed before the shank and handle assembly is inserted in the socketed plate 26, and it will be seen that after insertion thereof 25 a part of the pin 30 lies inside and is trapped by the socket. A soft rubber or other suitable buffer, as 21, may be provided upon the inside of the free end of the handle, to hold it at the desired distance from the door and prevent injury to the 30 door surface. The fit between the slotted portion 21' of the handle and the flattened head 39 of the shank 25 may be a close one, so that the turning moment applied to the handle is transmitted entirely through such inter-engaging 35 surfaces, without exertion of any effort on the spring or pin portions.

The shank 25 is preferably slidable bodily through the latch casing 15, at least through a slight travel; and longitudinal effort is exerted 40 upon the shank by a compression spring 50 arranged upon the shank between the socket portion 24 and the latch mechanism, and bearing inwardly at its inner end upon the shank to urge it, and accordingly the spherical end of the handle, into the socket. At its outer end the spring bears outwardly against the inner surface of the socket portion; retainers, as 51, being provided 45 for the spring ends.

The portion of the shank which extends 50 though the spring 50 is rounded, while that which extends through the latch mechanism is squared. The diameter of the round portion of the shaft is less than the thickness of the square section, the juncture of the round with the square portion, providing an abutment against which the inner spring retainer 51 engages. The construction of such retainer is best shown in Figure 6. The retainers and spring are assembled upon the shaft over the squared end, and the retainers are provided with squared openings of such size as 55 to enable them to slide freely thereover. At 45° to its squared opening the inner retainer is provided with a squared depression, 52, proportioned to fit over the abutment portion comprising the corners of the abutting squared section of the shaft, where the retainer is yieldably held by the spring, while the depressed portion in turn holds the retainer against turning and so prevents escape of the spring.

To provide a stop which is more massive than the pin and slot connection limiting outward movement of the handle, the head 39 of the shank

may be reduced in diameter throughout a part of its periphery, forming a shoulder 55 against which engages a shoulder 56 formed by complementarily reducing the diameter of the slot 21' in the ball section of the handle, to limit outward 5 movement of the handle.

What I claim is:

1. Extensible operating means of the character described comprising in combination with a support and a shaft limitedly slidable therein, a 10 socketed handle-supporting portion through which one end of said shaft slidably and rotatably projects, a handle lever pivoted to such projecting end of the shaft on a transverse axis and rotatable with respect to the shaft only about 15 such pivotal axis, said handle lever having at its pivoted end a ball portion limitedly movable universally in such socket portion, spring means arranged within the ball portion and acting upon the handle and the projecting end of the shaft, 20 to urge the handle lever toward the support about such transverse axis, and separate spring means reacting against the shaft to urge it longitudinally in a direction to maintain the ball portion seated in the socket portion, said pivotal connection between the handle lever and the shaft comprising a pin fast in the ball portion of the handle lever and rotatable in the shaft, said first-mentioned spring means comprising a torsion spring wrapped loosely about the pin within 25 the shaft, and also loosely mounted with respect to the shaft, and reacting against said pin and shaft.

2. An extensible latch handle comprising in combination with a handle shaft and a socketed 35 supporting portion through which an end of said shaft projects and in which it is rotatable, a handle lever pivoted to such projecting end of the shaft upon an axis transverse to the shaft for bodily rotation with the shaft and for swinging 40 movement about said transverse axis, torsion spring means arranged within the handle and reacting against the same for swinging the handle in a desired direction about said transverse axis, and separate spring means reacting against the 45 shaft and socket to urge the handle into the latter, said pivotal connection comprising a pin extending through the ball portion of the handle lever and shaft and lying at least partly in the socketed portion, said handle and shaft having 50 other portions transverse to the axis of the shaft and closely fitted, whereby turning moment applied to the handle is transmitted through said other portions rather than the pin.

3. An extensible latch handle comprising in 55 combination with a handle shaft and a socketed supporting portion through which an end of said shaft projects and in which it is rotatable, a handle lever pivoted to such projecting end of the shaft upon an axis transverse to the shaft 60 for bodily rotation with the shaft and for swinging movement about said transverse axis, torsion spring means arranged within the handle and reacting against the same for swinging the handle in a desired direction about said transverse 65 axis, separate spring means reacting against the shaft and socket to urge the handle into the latter, and interfitting pin and guide slot portions carried by said socket and ball portions to control the movement of the handle.
